UNITED STATES PATENT OFFICE

2,048,571

PADLOCK

Samuel C. Slaymaker, Lancaster, Pa., assignor to
The Slaymaker Lock Company, Lancaster, Pa.,
a corporation of Pennsylvania

Application April 29, 1936, Serial No. 77,023

9 Claims. (Cl. 70—108)

This invention relates to locks, and more particularly to padlocks, with reference to improvements in that class of such devices commonly known as the "sliding shackle" type.

5 One of the principal objects of the invention is to provide a lock of improved construction embodying a simplified inner locking mechanism adapted to be assembled easily and capable of being manufactured and sold at low cost as compared with less efficient locks of the same general character.

Another principal object is to provide a strong and sturdy lock having qualities of more expensive constructions built into its structure and 15 rendering it especially durable and "break" or "pickproof".

Other objects, in addition to the general concept and advantages of the invention, will appear and be best understood from the following 20 description with reference to the attached drawing, illustrating one practicable form and embodiment of the same already in commercial production.

In said drawing:

25 Fig. 1 is a front face elevation of a padlock comprising the invention;

Fig. 2 is a like view of the same with the front face part removed to reveal its inner structure and operative elements, shown in locked position;

30 Fig. 3 is an elevational view of the removed front face part inverted;

Fig. 3^a is a fragmentary view thereof illustrating a detail of possible modification;

Fig. 4 is a side or edge view of the same part;

35 Fig. 5 is a view corresponding to Fig. 2, showing the operating key inserted with the operative elements still in locked position;

Fig. 6 is a similar view, partially in longitudinal section, showing the key turned and the 40 operative elements in unlocked position;

Fig. 7 is an edge or side longitudinal section taken on the line 7—7 of Fig. 1;

Fig. 8 is a transverse section taken on the line 8—8 of Fig. 5, looking down as indicated by the 45 arrows;

Fig. 9 is a fragmentary view of a part of Fig. 6, illustrating a modification;

Fig. 10 is a detail perspective view of one of the lock elements; and

50 Fig. 11 is a like view of a modification of the latter.

The illustrative lock comprises a special form of casing, or casing member, 12 and a generally conventional J-shaped shackle 13 slidable therein, combined with locking elements allowing the shackle to be withdrawn and swung on its longer arm pivot when released by an opening key.

55 Said casing, or casing member, 12 consists of a single or solid piece of strong metal cast or 60 molded into a hollow cavitated body of essentially

rectangular block form, having a substantial wall thickness throughout rendering it uncommonly strong. The front and back faces thereof are in this instance formed with circular centers (see Fig. 1) defined by edges or ridges 5 12^a, the back one of which centers is superficially convexed for added strength and harmony of design, and the front one of which centers is provided with an opening 14 therein making the casing effectually open-faced so that the associated parts can be assembled therein easily and conveniently. Around the inner side of said opening a shoulder 12^b is formed in the side wall of the body, and across said opening parallel pairs one horizontal and one vertical of partition walls 12^c—12^d and 12^e—12^f extend from the back wall of the body in T relation to each other (see Fig. 2), said shoulder and partition walls being on a level with each other for a purpose which will be explained presently. At one side, 10 inner thickened wall portions or buttresses 12^g and 12^h in the body are formed on opposite sides of the partition walls 12^c and 12^d, or with a space 15 therebetween, these being for a purpose also to appear. At the top, the casing body is desirably formed with what may be called "post" 20 portions 12' and at the bottom a hole 16 provides for insertion of a key.

The aforementioned opening 14 in the front face of the casing is closed by a cover plate 17 30 fitted thereto and secured in place by crimping or swaging the surrounding edge or ridge 12^a of the casing marginally thereover. This plate is externally convexed correspondingly to the back wall of the casing for conformity with its 35 design, but is flat on the inner side (see Figs. 3 and 4). It rests squarely upon the co-level inner annular shoulder 12^b and cross-wise T related partition walls 12^c—12^d and 12^e—12^f of the casing so as to be held firm and solid in position, and 40 jointly with the back wall is thereby rigidified against the likelihood of breaking or crushing from blows struck upon it. A lug 17^a on its inner side fits into a recess formed in the cross-wise partition wall 12^c, resting upon the latter, and the two 45 are jointly apertured to provide a bearing hole 18 for the end of a key (see Fig. 7). A second shorter lug 17^b thereon fits into a similar recess formed in the cross-wise partition wall 12^d and together therewith forms a ward for the key, 50 and a third lug 17^c rests retentively on a key-guard 19 fitted in the casing across the key-hole 16 at the bottom.

The aforementioned shackle 13 extends into the casing through the "post" portions 12' at the 55 top, with its longer arm 13^a rotatably fitting in an elongated recess 20 provided through the thickened wall portion or buttress 12^g and into the adjacent portion or buttress 12^h and so spanning the space 15 between the two (see Fig. 6), 60

and with its shorter arm 13^b fitting into an abbreviated recess $20'$ provided in the "post" portion at the opposite side. Guided to slide and swivel in its receptive bore, said longer arm of the shackle is formed with a side recess 21 at its end merging into a subjacent annular groove or reduced portion $21'$, and into this recess a pin 22 engages to limit the outward slide movement by a shoulder striking thereagainst while allowing the arm to swivel by reception within the groove. Said pin, fitting through a hole in the buttress wall beside the shackle arm, is primarily shown to be provided as a separate element retained in place within said wall, but it may instead advantageously and sometimes preferably be formed as a projection part of the cover plate 17 —which bears against it—as illustrated in the detail Fig. 3^a. This would of course have the advantage of decreasing the actual number of separate parts. Said longer arm is also formed with detents 23 in opposite sides, at the point of spanning the space 15 between the thickened wall portions or buttresses 12^a and 12^b when in the locked or fully inserted position. The purpose of these will be explained presently. A spring 24 applied under the same arm within its receptive bore serves to expel the shackle with a "snap" action when it is released from the locked position.

Fitted in the space between the horizontally cross-wise partition walls 12^a and 12^b is a locking pawl member comprising a spring 25 of hair-pin form, having its legs 25^a and 25^b straddling the longer arm of the shackle and engaging normally in the detents 23 of the same (see Figs. 2 and 7). The spring action of this member of course tends to press the two legs thereof together and so keeps them firmly engaged with the shackle, with no possibility of shaking or even forcing apart by a pull upon the shackle. It is retained in place by the walls which encompass it, the back wall and cover plate of the casing contributing to a complete boxing on all sides and the back wall being additionally recessed accommodatively thereto, so that it is held tight and secure without need of other fastening.

Between the vertically cross-wise partition walls 12^a and 12^b a series of slots 26 is formed in the back wall of the casing body (see Fig. 2), with a corresponsive ribbing $26'$ of the partition wall at one side, and a similar correlated series of slots 27 are formed in the inner surface of the cover plate (see Fig. 3). These slots provide for one or more key-wards 28 to be fitted into place between said partition walls and between said back wall and cover plate of the casing, depending upon choice and upon the key designed to fit the lock, the series slots allowing for different ward and key combinations. Only one ward is shown in Figs. 2, 5 and 6, which coupled with the ward formed by the cover plate lug 17^b and its opposed recessed portion of the partition wall 12^b really makes two, but the modification of Fig. 9 shows three wards set selectively in the slots and so of course complicating the key accommodation. Said wards 28 in this instance comprise mere plate members having a lug 28^a either at one end (see Fig. 10), or at both ends (see Fig. 11), adapted to fit in any of the slots of either the back wall or cover plate, or both, and a width to fit snugly between said partition walls 12^a and 12^b with side balancing between the ribbing or ribs $26'$ in the one of said walls. Thus fitted in place the wards are held tightly secure and cannot be dislocated from position by shaking or striking the lock. Central slot-and-

circular openings 29 therein provide for key passage and turning of the proper key, whereas a false or non-fitting key may be inserted but cannot be turned therein.

In Fig. 5, a fitted key 30 is shown inserted into place with its tip end extending into the bearing opening 18 therefor formed between the lug 17^a and opposed portion of the wall 12^a , and with predetermined side-cuts therein registering with the respective ward openings—one being the ward 10 28 and the other being the ward formed by the lug 17^b and wall 12^b as before mentioned. In this position the end passes between the legs of the spring pawl member 25 (see also Fig. 7) and is so adapted to spread said legs apart when turned. However, said key in this figure has not been turned and the operative elements remain still in locked position. Fig. 6 shows the key turned a full ninety degrees with its end spreading the spring legs apart and the shackle thereby released to the limit of its outward ejected position. Thus released, the shorter arm may be swung in either direction on its longer arm pivot as common to locks of the character.

The strength and simplicity of this construction will be appreciated, while the advantage of the solid and anti-loose assembly of parts will be apparent. Other advantages of the improvement will be recognized by those familiar with lock manufacture, including the open face structure facilitating the placement and assemblage of the operating parts and the elimination of all fastening therefor, the various parts being merely dropped into place and the cover plate being then applied.

It will be obvious of course that various changes in form and arrangement of parts, and different combinations and subcombinations thereof, can be made without departing from the intent and scope of the invention. For instance, the shackle check or stop pin may be made a part of the cover plate and any number of key wards may be employed as before stated, or the wards might be differently formed and placed, or adapted to a different kind of key. Other variations as well might be adopted. Therefore, it is not intended to limit the invention by the appended claims to the specific arrangement illustrated and herein-before explained in detail.

Having thus described my invention, what I claim as new and desire to secure by Letters Patent of the United States is:

1. A padlock, comprising a metal casing body having an opening in its front face, a cover plate secured in said opening, a shackle extending into the casing with an arm journaled in side wall portions of the same thickened to receive it, a spring pawl member having legs engaging said arm of the shackle at opposite sides between said wall portions, means limiting the outward sliding movement of the shackle upon release, a passage for a key to extend between the legs of the pawl member so as to spread them apart to release the shackle arm, and at least one key ward inserted in said passage, said ward being secured between the back wall and cover plate of the casing by endwise fit into slots formed in each.

2. A padlock according to claim 1, wherein the ward secured in the key passage comprises a centrally apertured plate having an end formed to fit into any one of a series of slots formed in said back wall and in said cover plate of the casing.

3. A padlock according to claim 1, wherein the ward secured in the key passage comprises a

- centrally apertured plate having opposite ends adapted to fit into any one of a series of opposed corresponding slots formed in said back wall and cover plate of the casing.
- 5 4. A padlock, comprising a metal casing body having an opening in its face, a cover plate secured in said opening with an inward rest upon a shoulder formed therearound, a shackle extending into the casing with an arm slidably journalled in side wall portions of the same thickened to receive it, a spring pawl member having legs engaging said arm of the shackle at opposite sides between said wall portions, a stop pin also engaging said arm of the shackle to limit its outward sliding movement, a key passage extending between the legs of said pawl member so that a key inserted therewith may be turned to spread them apart to release the shackle arm, and removably fixed key wards secured in 10 said passage between the back wall and cover plate of the casing by engagement in one or the other of the same having receptive means therefor.
- 5 5. A padlock, comprising a solid metal cavitated casing body having thickened wall portions and an opening in its face, a cover plate secured in said opening and bearing inwardly upon a shoulder formed therearound, a shackle extending into the casing with an arm slidably journalled in said thickened wall portions thereof at one side, a spring pawl member having legs engaging said arm of the shackle at opposite sides between said wall portions, a stop pin fitted in the casing wall also engaging said arm of the shackle to limit the 15 outward slide movement thereof, a key passage extending between the legs of said pawl member providing for the insertion of a key to be turned so as to spread them apart to release the shackle arm, and one or more key wards placed in said 20 passage with a securing between the back wall and cover plate of the casing by endwise fitting into one or more opposed slots formed in the latter, combined with a key-guard at the entrance of said key passage.
- 45 6. A padlock, comprising a solid metal cavitated casing body of substantially rectangular block form having front and back circular face portions with an opening in the front portion making it effectually open-faced, parallel pairs of partition walls extending from the back wall of the casing in T relation across said opening, a cover plate fitably secured in said opening upon a shoulder therein and against said pairs of partition walls, a shackle extending into the casing 50 with an arm slidably journalled in body wall portions of the same on opposite sides of one pair of the partition walls at one side of the casing, a spring pawl member fitted between said one pair of partition walls having legs engaging said arm of the shackle at opposite sides between said body wall portions, a stop pin extended through one of the journaling wall portions into engagement with 55 said arm of the shackle to limit its outward sliding movement, a key passage formed in the other of said pairs of partition walls and extending between the legs of said pawl member for inserting a key to be turned to spread said legs apart in release of the shackle arm, and at least one key ward secured in said passage between 60 said other pair of partition walls with a fitting into any of a series of slots formed in one of said other pair of partition walls.

7. In a padlock, a solid metal casing body having front and back face portions with an opening in one of said portions making it effectually open-faced, a shoulder formed around the inner edge of said opening, parallel pairs of partition walls extending from the back wall of the casing body in T relation across said opening flush with said inner shoulder, a cover plate fitted in said opening against the shoulder and said cross-wise pairs of partition walls, a spring pawl member having inwardly pressed legs fitted between one of the pairs of partition walls, key wards disposed between the other pair of partition walls and there within providing a key passage extending between the legs of the spring pawl member, one of said 15 wards being formed by and the remaining being removably engaged between the back wall and cover plate portions of the casing, a shackle extending into the casing with one arm passing between the legs of the spring pawl member and engageable thereby for locking, and means limiting the released sliding movement of the shackle; said cover plate being secured in the aforesaid opening of the casing with surrounding edge portions of the casing body marginally overlapping 20 the same.

8. A padlock, comprising a metal casing body having thickened wall portions at one side and an opening in its front face, a cover plate fitted and secured in said opening, a shackle extending into the casing with an arm journalled in said thickened wall portions at one side, a spring pawl member having legs engaging said arm of the shackle between said wall portions, means limiting the outward sliding movement of the shackle upon release, a passage for a key to extend between the legs of the pawl member so as to spread them apart to release the shackle arm, and at least one key ward disposed in said passage, said 30 ward being secured between partition walls 35 formed in the casing body by fit into any one of a series of slots formed in said partition walls.

9. A padlock, comprising a solid metal cavitated casing body having front and back circular face portions with an opening in the front portion making it effectually open-faced, parallel pairs of partition walls extending from the back wall of the casing in T relation across said opening, a cover plate fitted and secured in said opening upon a shoulder therein and against said pairs of partition walls, a shackle extending into the casing with an arm slidably journalled in body wall portions of the same on opposite sides of one pair of the partition walls at one side of the casing, a spring pawl member fitted between one of said pairs of partition walls having legs engaging said arm of the shackle between said body wall portions, a stop pin extended through one of the journaling wall portions into engagement with 60 said arm of the shackle to limit its outward sliding movement, a key passage formed in the other of said pairs of partition walls and extending between the legs of said pawl member for inserting a key to be turned to spread said legs apart in release of the shackle arm, and at least one key ward secured in said passage between said other pair of partition walls with a fitting into any of a series of slots formed in one of said other pair of partition walls.
